(57) **CLAIM**

The ornamental design for a camera, as shown and described.

DESCRIPTION

[1. Camera
1.1 : Top
1.2 : Back
1.3 : Perspective
1.4 : Bottom
1.5 : Right
1.6 : Front
1.7 : Left]

FIG. 1 is a top front perspective view of a camera showing the claimed design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof; and,

FIG. 7 is right side elevation a view thereof.

The dot-dash broken lines in the figures and the area(s) within the dot-dash broken lines show portions of the camera that form no part of the claimed design.

1 Claim, 7 Drawing Sheets

Matter enclosed in heavy brackets [ ] appears in the original patent but forms no part of this reissue; matter printed in italics indicates the additions made by reissue.

[AMENDED]
